HEAT DISSIPATION OF DYNAMIC BRAKES

Edgar J. Justus, Atlanta, Ga.

Application May 21, 1947, Serial No. 749,575

9 Claims. (Cl. 290—9)

1

My invention relates to dynamic braking and more particularly to a system and method for disposing of the energy created in dynamic braking.

Diesel-electric locomotives now in operation in mountain service use dynamic braking on long downhill grades. The electric traction motors are turned into generators and the electrical energy created by the motors is converted to heat energy in resistor units. One method of dissipating this heat energy is by cooling the resistors with air blown over them by fans built into the resistor banks. This method is not satisfactory because it requires a large resistor bank and a large fan to dissipate the large amount of energy created. The resistor bank and fan require a large amount of space, which is at a premium in a locomotive. Also, they add a substantial amount of weight to the locomotive.

Another method commonly used for dissipating the heat energy is to mount the resistors in the bank of radiators for the cooling fluid of the diesel engine which is the prime mover. The resistors in such an arrangement are cooled by the air flowing over the bank of radiators. This method is objectionable because the dynamic braking is used only when the engine is idling and the cooling fluid is not being heated by the engine. The cooling fluid in the radiators is consequently cooled, by the flow of air needed to cool the resistors, to a very low temperature. The fluid, in turn, cools the cylinder and cylinder head of the engine to a low temperature. That low temperature is undesirable because a wide variation in temperature contributes to cracking of the cylinder and the cylinder head.

The present invention concerns a novel method of dissipating the heat created in resistors for absorbing the electrical energy generated in dynamic braking, which method avoids the objections to the prior methods described above.

One object of my invention is to provide a system for dissipating the heat created by conversion of the electrical energy generated in dynamic braking to heat energy in apparatus which is relatively compact and light in weight.

Another object is to provide a system and method for dissipating the electrical energy created in dynamic braking which comprises converting the electrical energy into heat and transferring the heat to the liquid in the cooling circuit of an internal combustion engine.

A further object is to provide a system for dissipating the energy created in dynamic braking as heat added to the cooling fluid of an un-

2

loaded internal combustion engine, thereby maintaining the engine at an elevated temperature.

Still another object of my invention is to provide a system for dissipating the energy created in dynamic braking as heat added to the cooling fluid of an internal combustion engine which system includes, for cooling said fluid, a fan whose speed is automatically varied with the amount of energy to be dissipated.

10 A still further object of my invention is to provide a system for dissipating the energy created in dynamic braking as heat added to the cooling fluid of an internal combustion engine, which system includes means for circulating said fluid in proportion to the amount of energy to be dissipated.

15 A clear understanding of my invention may be had by reference to the accompanying drawing, in which the single figure is a diagrammatic representation of the cooling fluid and electrical connections for the braking system.

20 In the drawing, a prime mover, such as an internal combustion engine, is indicated by the reference numeral 1. This engine may, for example, be a diesel engine such as those used in diesel-electric locomotives and drives a generator 2 through a shaft 3. The generator creates electrical energy which, through electrical conduits 4 energizes the electrical traction motors 6 and thereby drives the locomotive.

25 When the locomotive is going downhill, gravity furnishes the motive power and only a very small relative current is required of the generator to excite the fields 5 of the traction 30 motors. Accordingly, engine 1 is idling when the locomotive is on a down grade. At such time the motors 6 are used for braking and, in such use, develop a large amount of electrical energy. This energy is conducted from the motors

35 through commutator brushes 7 and electrical conduits 8 to resistance coils in a resistor box 9, in which most of the electrical energy is converted into heat.

40 The engine 1 is cooled by a fluid, such as water, circulated through its cylinder wall jackets. In cooling the engine, the fluid absorbs heat and is pumped through pipe 10 from the engine by a main circulating pump 11, which may be driven through a shaft 12 and suitable reduction gearing by engine 1 so that the speed of the pump is proportional to the speed of the engine. From the pump 11, the fluid flows through a pipe 13, an auxiliary pump 14 and a pipe 15 to the resistor box 9. The latter is illustrated only diagrammatically in the drawing but is constructed

with separate passages for the fluid and the resistance coils, so that the latter are insulated electrically from the fluid but are in heat exchange relationship therewith. When electric current is passing through the resistance coils, they become heated and their heat is carried off by the fluid, which leaves the resistor box 9 through pipe 16 conducting it to the radiator 17.

The pump 14 is necessary because in braking when the engine is idling, there is insufficient circulation for maximum heat transfer. The pump 14 is driven through a shaft 18 by an electric motor 19, which is connected by leads 20 across an appropriate number of coils in the resistor box 9. It is apparent that the voltage impressed across leads 20, and therefore the speed of motor 19 and pump 14, will be proportional to the load on the resistor box 9. Thus, the amount of cooling fluid circulated by the auxiliary pump 14 will be proportional to the amount of heat to be dispersed from the resistor box 9. Both pumps 11 and 14, being centrifugal pumps, do not offer any resistance to flow through them. Whichever pump is being driven does the circulating and the other is just a slight restriction in the piping.

In the radiator 17, the fluid is cooled by air blown over the radiator coils by a fan 21, which is driven by an electric motor 22. The fan motor is driven by power from the generator when the locomotive is loaded and appropriate switches disconnect it from the generator and hook it to the resistors when the unit is in braking. Thus, I use the same fan for cooling both in braking and in normal operation. The motor 22 is connected by leads 23 across an appropriate number of coils in the resistor box 9. It will be appreciated that, as in the case of the motor 19, the speed of the motor 22 and of the fan 21, when connected to the resistors for braking will be in proportion to the load on the resistor box 9. Accordingly, the weight of air blown over the radiator 17 by the fan 21 will vary directly with the amount of heat to be dissipated from the resistor box 9 and, through the cooling fluid, from the radiator 17.

After the fluid is cooled in the radiator 17, it passes therefrom through the conduit 24 to the cylinder wall jacket of the engine 1, where it serves the function, when the engine is loaded, of removing the heat of combustion. When the engine is not loaded, but is instead idling, the fluid passes through the engine jacket without being heated. This is the instance when the locomotive is going downhill and the dynamic braking is being used, so that there is a load on the resistor box 9 and the fluid removes the heat created in the resistance coils.

An expansion tank, or surge tank, 25 may be included in the system at a proper place to provide for variations in volume and pressure of the cooling fluid.

A further feature of my invention is illustrated in the louvres or shutters 26 on the radiator 17, in front of the fan 21. These shutters are preferably controlled automatically through the duct 27 by the thermostat 28, which is inserted in the fluid conduit 24. The function of the thermostat 28 and the shutters 26 is to maintain the temperature of the fluid entering the engine 1 at a certain minimum and maximum to avoid a wide variation in the temperature of the cylinder walls and thus reduce the possibility of the cylinders becoming cracked. This is accomplished by the thermostat 28 acting, when the temperature of the cooling fluid becomes low, to

close the shutters 26 and thereby to restrict or shut off the flow of air from fan 21 over the radiator 17. Conversely, when the temperature of the fluid becomes high, the thermostat 28 acts to open the shutters 26 and thereby permit a greater flow of air from the fan 21 over the radiator 17.

It will be readily seen that I have provided a practical and efficient system for disposing of the heat generated in dynamic braking requiring a minimum of apparatus. The apparatus used in this system is compact, requiring a minimum of space and adding a minimum of weight. The apparatus required in this system is smaller and of less weight than that of prior systems because the weight and size of resistors which are cooled by a circulating liquid is much less than the weight and size of resistors which are cooled by air.

When the engine 1 is running at full load, approximately as much heat is given off to the cooling fluid and through it to the radiator 17 as goes into useful work in the traction motors. Accordingly, the radiator 17 has a capacity for heat dissipation which is about equal to the brake horsepower of the engine. When the engine 1 is idling, and the traction motors 6 are used in dynamic braking, the maximum load on the motors is roughly equal to the maximum brake horsepower of the engine 1. Therefore, the maximum amount of heat created in the resistor box 9 and to be dissipated in the radiator 17 is approximately equal to the capacity of the radiator, so that the radiator can adequately dissipate the heat of braking.

Because heat is added to the cooling fluid in the resistor box 9, the engine 1 is not cooled to too low a temperature during long downhill runs when the engine is idling. As explained hereinabove, the control of the shutters 26 by the thermostat 28 further aids in maintaining the temperature of the cooling fluid at a certain minimum, so that damage to the engine from cracking of the cylinders is avoided.

It is to be understood that the system of my invention is not limited to use in locomotives, but has other applications. For example, it may be used with engine-electric mine hoists where the engine cooling system can be used to dissipate the energy generated in braking the lowering of heavy loads dynamically, instead of using a brake band or brake shoes.

It will be seen that my system provides for adequate heat dissipation in braking equal to the heat dissipation taking place at full load in traction without requiring addition to the normal radiator capacity or the addition of extra fans. This is made possible by the novel idea of introducing the heat to the engine cooling system at a time when it is otherwise idle.

I claim:

1. A dynamic braking system in which the electrical energy generated in braking is converted to heat in a resistor and said heat is absorbed in the cooling circuit of an internal combustion engine, said cooling circuit including a heat exchanger and a fan for circulating air over said heat exchanger, said fan being driven by a motor energized from said resistor, whereby the speed of said motor and of said fan varies with the load on said resistor.

2. A dynamic braking system for use in connection with an internal combustion engine-electric traction motor drive having a cooling fluid circulating system, comprising a resistor for

expending the power developed by said traction motor in braking and an auxiliary pump for circulating said cooling fluid through said resistor, said pump being driven by a motor energized from said resistor, whereby the speed of said motor and of said pump varies with the load on said resistor.

3. In a dynamic braking system in which a cooling fluid is circulated between a heat exchanger and the engine to cool the engine, the improvement comprising a resistor to convert the electrical energy generated in the braking system to heat, and a pump directing cooling fluid from the engine in heat transfer relationship with the resistors, said pump being driven by a motor energized by the resistors, whereby the rate of circulation of the cooling fluid is determined by the load on the resistors.

4. In a dynamic braking system in which a cooling fluid is circulated between a heat exchanger and the engine to cool the engine, the improvement comprising a resistor to convert the electrical energy generated in the braking system to heat, means to direct the cooling fluid from the engine in heat transfer relation with the resistors and to the heat exchanger, and a fan passing air over the heat exchanger for removal of heat therefrom, said fan being driven by a motor energized by the resistors whereby the rate of circulation of air over the heat exchanger is determined by the load on the resistors.

5. In a dynamic braking system in which a cooling fluid is circulated between a heat exchanger and the engine to cool the engine, the improvement comprising a resistor to convert the electrical energy generated in the braking system to heat, a pump directing cooling fluid from the engine in heat transfer relationship with the resistors, said pump being driven by a motor energized by the resistors, whereby the rate of circulation of the cooling fluid is determined by the load on the resistors, and a fan passing air over the heat exchanger for removal of heat therefrom, said fan being driven by a motor energized by the resistors whereby the rate of circulation of air over the heat exchanger is determined by the load on the resistors.

6. A dynamic braking system for an internal combustion engine-electric motor drive comprising a cooling system for the internal combustion engine including a heat exchanger and means for circulating a cooling fluid between the engine and the heat exchanger, a resistor electrically connected to the electric motor and heated by electrical current generated by the motor as the motor serves as a brake, means directing the cooling fluid of the cooling system in heat conducting contact with the resistors to extract the heat generated in the dynamic braking therefrom and then to the heat exchanger of the cooling system as the cooling fluid is circulated therethrough, and means responsive to the heat generated by the resistors for controlling the rate of dissipation of heat whereby the rate of dissipation of heat is increased with the load on the resistors.

7. A dynamic braking system for an internal combustion engine-electric motor drive comprising a cooling system for the internal combustion engine including a heat exchanger and means for circulating a cooling fluid between the inter-

nal combustion engine and the heat exchanger, a resistor electrically connected to the electric motor and heated by electrical current generated by the motor as the motor serves as a brake, means directing the cooling fluid of the cooling system in heat conducting relationships with the resistor to extract heat therefrom and then to the heat exchanger of the cooling system as the cooling fluid is circulated, and means for controlling the amount of heat extracted from the cooling liquid in the heat exchanger to control the temperature of the cooling fluid leaving the heat exchanger.

8. A dynamic braking system for an internal combustion engine-electric motor drive comprising a cooling system for the internal combustion engine including a heat exchanger and means for circulating a cooling fluid between the internal combustion engine and the heat exchanger, a resistor electrically connected to the electric motor and heated by electrical current generated by the motor as the motor serves as a brake, means directing the cooling fluid of the cooling system in heat conducting relationships with the resistor to extract heat therefrom and then to the heat exchanger of the cooling system as the cooling fluid is circulated, and thermostatic actuated means to control the amount of heat removed from the cooling fluid in the heat exchanger to control the temperature of the cooling fluid circulated to the internal combustion engine.

9. A dynamic braking system for an internal combustion engine-electric motor drive comprising a cooling system for the internal combustion engine including a heat exchanger and means for circulating a cooling fluid between the engine and the heat exchanger, a resistor electrically connected to the electric motor and heated by electrical current generated by the motor as the motor serves as a brake, means directing the cooling fluid of the cooling system in heat conducting contact with the resistors to extract the heat generated in the dynamic braking therefrom and then to the heat exchanger of the cooling system as the cooling fluid is circulated therethrough, an auxiliary pump for circulating the cooling fluid and an auxiliary motor energized by the electrical current generated when the electric motor serves as a brake adapted to drive the auxiliary pump.
